5 Claims. (Cl. 200—9)

This invention relates to an arrangement for controlling a sequence of different operations, in particular of a chemical cleaning machine. In known manner, in the mechanism there is provided a drum switch whose control drum includes cams for actuating pushers of electric switches and/or valves.

Hitherto such arrangements with drum switches had the disadvantage that, during rotation of the drum from one working position to the next, the switches and/or valves were moved into other positions by the rising or sloping flanks of the cams, which naturally took a certain time, leading thereby temporarily to unforeseen and often disadvantageous switching conditions.

The present invention permits of eliminating the described disadvantage and consists principally in that the switches or valves are arranged on at least one side plate which is movable into two positions, whose distance from the axis of the drum is variable and which permits the pushers of the switches or valves to be lifted off the cams of the drum, when the latter is rotated.

In this design, the cams need not have sloping flanks and, in the movement of the side plate towards the drum—which may take place at high speed as compared with the rotation of the drum—all the relevant switches or valves are actuated simultaneously. Thus unforeseen and undesired switching conditions are avoided.

Further features of the invention will appear from the following description and claims, taken in conjunction with the accompanying drawing, wherein there is shown, purely by way of example, one preferred form of embodiment incorporating the invention.

In said annexed drawing:

FIG. 1 shows diagrammatically a chemical cleaning machine in connection with an arrangement according to the invention for controlling the different operations of the machine;

FIG. 2 represents a sectional view of the drum switch of the control mechanism alone, i.e. with the side plates moved clear of the drum;

FIG. 3 is a similar representation with the side plates moved towards the drum;

FIG. 4 shows a diagrammatic longitudinal section through the drum switch;

FIG. 5 is a sectional view taken on the line V—V of FIG. 4;

FIG. 6 is a sectional view taken on the line VI—VI of FIG. 4;

FIG. 7 is a view from the right in FIG. 4;

FIG. 8 is a part-sectional view similar to FIG. 3, but in another position;

FIG. 9 shows in perspective view an impulse transmitter for automatic operation of the control mechanism;

FIG. 10 represents the development of the periphery of

2

two camisks of the impulse transmitter and the electrical control impulses produced therewith;

FIG. 11 is a view of a pneumatically operated gate valve of the cleaning machine; and

5 FIG. 12 is a top view of the gate valve with the pneumatic cylinder removed.

Referring to FIG. 1, the chemical cleaning machine shown includes a drum casing 10 which has rotatably arranged therein a sieve drum (not shown) to take the material to be cleaned, say, textiles. A pipe 11 is connected to the top of the drum casing 10, the other end thereof being connected to the delivery side of a feed pump 12. The suction side of the pump 12 is connected through two gate valves 13, 14 and associated pipes 15, 16, 17 to two storage tanks 18 and 19 for washing liquids. The tank 18 contains a liquid for preliminary washing, and the tank 19 a liquid for final washing of the material to be cleaned. A runoff 20 from the drum casing 10 leads to a sieve 21, whence a pipe 23 fitted with a gate valve 22 leads back to the pipe 15 connected to the suction side of pump 12. Each of the gate valves 13, 14, 22 has allocated thereto a pneumatic cylinder 24, 25 and 26 respectively with a piston movable therein and adapted to actuate the associated gate valve. The design of a unit comprising a gate valve and an associated pneumatic cylinder will be described in greater detail as description proceeds with reference to FIG. 11. Two pipes 27 and 28 are connected at one end to each of the cylinders 24, 25 and 26 and at the other end to a drum switch 30 that will be described below in detail with reference to FIGS. 2-8.

20 The drum switch 30 includes a rotatably supported drum 31 which may be driven by a handwheel (FIG. 4). The drum 31 has firmly joined thereto a notched disk 33 which, according to FIG. 5, has a plurality of notches spaced equidistantly along its periphery and which can be engaged by a roller 34. Said roller is mounted on a lever 35 which is rockable about an axis 35 and is under the action of a spring 37 that tends to keep the roller 25 in engagement with one of the notches to thereby secure the drum in the set position.

25 The frame 39, merely indicated in FIG. 4 and supporting the shaft 38 of drum 31, comprises two side plates 40 and 41 which are pivotally mounted on pins 42 and 43 so that the drum is positioned therebetween. By pivoting said plates, the distance thereof from the axis of drum 31, and hence also from the drum itself, may be altered.

30 The plates 40 and 41 include extensions 44 and 45 that are coupled to each other through a link 46. In this way, a symmetrical and synchronous movement of said plates with respect to the drum 31 can be positively achieved. Interposed between the two plates 40 and 41 is a compression spring 47 which tends to force apart the plates and from the drum 31. A pneumatic cylinder 48 is connected through a hinge-pin 49 with one side plate 41, while a piston 50 movable in cylinder 48 has a piston rod 51 which, by means of a hinge-pin 52, is pivoted to the other plate 40. One end of the cylinder 48 communicates through a pipe 53 with a distributor pipe 55 carrying compressed air at a pressure of, say, 8 atm.

35 Inserted in pipe 53 is a valve 57 which is operated by an electro-magnet 56. One side plate 40 has attached thereto two commercial-type pneumatic change-over valves 60 and 61, and the other side plate 41 contains a similar valve 62, all valves

40 45 50 55 60 65

being connected through a pipe 63 to said distributor pipe 55. Said valves 60, 61, 62 have furthermore attached thereto two pipes 27 and 28 which lead to the pneumatic cylinders 24, 25 and 26. Each valve 60, 61 and/or 62 has also a vent 64 to the open air, as well as an actuating element 65 in the form of a push-button which is movable against the action of a resetting spring in the valve. The valve 60 has allocated thereto a rocker arm 66 which, by means of a pin 67, is pivoted to the side plate 40. A leaf spring 68 is fixed to the rocker arm 66 and cooperates further with the actuating element 65 of valve 60. The rocker arm 66 lies opposite one end of a sliding bolt 69 which is mounted on plate 40 for longitudinal displacement and serves as a pusher for operating the valve 60 through the rocker arm 66 and leaf spring 68. The sliding bolt extends substantially radially to the axis of drum 31. In an entirely similar way, each of the other valves 61 and 62 also has associated therewith a sliding bolt 69 that serves as a pusher, a rocker arm 66 pivoted to the respective side plate and a leaf spring 68 fixed thereto.

The plate 41 has mounted thereon a commercial-type electric switch 71 which, under the action of a resetting spring, always tends to take up its position of rest, in which the connected circuit is opened. An actuating element 72 of said switch 71 is located in front of one end of a sliding bolt 73 which serves as a pusher and is supported on plate 41 for longitudinal displacement so as to extend substantially radially to the drum 31. The switch 71 lies in the control circuit 75 of a motor contactor 76 which, on the one hand, is connected to the supply network 77 and, on the other hand, by means of an electric supply line 78 to an electric motor coupled to the pump 12, as shown in FIG. 1.

The cylindrical surface of the drum 31 contains a plurality of cams 80, only a part of which is illustrated in FIGS. 2 and 3. The arrangement of the cams 80 is such that, in every position of the drum 31, at least one of the cams will be located in front of one of the sliding bolts 69 and 73 so that, upon movement of the plates 40, 41 towards the drum 31, the respective sliding bolt and hence also the associated valve 60, 61 or 62 or the associated switch 71 will be operated. The cams 80 may, for instance, be the heads of screws inserted in tapped holes in drum 31. This has the advantage that the cams may be mounted or removed in a simple way as required, if necessary also subsequently.

According to FIG. 8, one plate 41 has arranged thereon an additional sliding bolt 82 approximately radial to the drum 31. This bolt 82 is under the action of a spring 83 which tends to push the bolt 82 towards the axis of drum 31. Circumferentially, the drum 31 is provided with a series of drilled holes into which the bolt 82 can fall under the action of spring 83 if the drum is in any of its rotary positions as determined by the notched disk 33 and roller 34 (FIG. 5) and the plates 40, 41 are moved towards the drum 31. The sliding bolt 82 then acts as a lock to prevent rotation of the drum 31 as long as said plates are not moved outwards clear of the drum 31.

In the vicinity of the notched disk 33 there is fixed an electric switch 85 (FIG. 5) which includes an actuating element 87 fitted with a feeler roller 86 and always tends, under the action of a built-in spring, to take up its position of rest, in which the connected circuit is closed. The feeler roller 86 then always engages one of the notches in disk 33 when the roller 34 also engages another notch. As the drum 31 rotates from one operating position to the next, the switch 85 is temporarily opened. According to FIG. 1, the switch 85 lies in the circuit of the electro-magnet 56 for operating the valve 57. This arrangement ensures that the valve 57 cannot be opened as long as the drum 31 takes up any intermediate position between two consecutive operating positions as determined by the notched disk 33 and roller 34.

In the circuit of the electro-magnet 56 there are further a manual operating switch 90 and a manual change-over switch 91 adapted to selectively switch-over the arrangement to manual or automatic operation. The additional means required for automatic operation will be described later as description proceeds.

With manual operation, the action of the aforescribed arrangement is as follows:

The changeover switch 91 is brought into the position shown in FIG. 1. Suppose now the drum 31 of the drum switch 30 be in its first operating position. If switch 90 is closed, the electro-magnet 56 will be energized and the valve 57 opened. From the distributor pipe 55 compressed air then flows through the pipe 53 into cylinder 48, whereby the two side plates 40 and 41 will be moved towards each other and the drum 31 against the action of spring 47. By suitably arranged cams 80 of drum 31, the electric switch 71 and changeover valve 60 are operated. The switch 71 closes the control circuit of contactor 76 which in turn closes the circuit of the driving motor of pump 12 which is thus started up. The valve 60, however, permits compressed air to flow from the pipe 55 into the cylinder 24 so as to cause the gate valve 13 to open. The other gate valves 14 and 22 are closed. Now the pump 12 delivers preliminary washing liquid from the tank 18 into the drum casing 10, as illustrated in FIG. 1. Subsequent to this, the hand switch 90 is opened to break the circuit of the electro-magnet and close the valve 57. The latter opens at the same time a vent to the open atmosphere, permitting air to escape from cylinder 48. Under the action of spring 47 the side plates 40, 41 are moved outwards, so that the sliding bolts 69 and 73 serving as pushers are lifted from the cams 80 of drum 31. The switch 71 then opens the control circuit 75 of contactor 76 which in turn stops the driving motor of pump 12. The changeover valve 60 now permits air from the cylinder 24 to escape into the atmosphere and at the same time air to flow from the pipe 55 to the other side of the piston in cylinder 24, thus closing the gate valve 13.

After the drum 31 has turned into the next operating position, the switch 85 is again closed and the plates 40 and 41 again move towards the drum 31. Now other cams 80 of the drum become effective in such a way that, by means of the changeover valves 60, 62 and pneumatic cylinders 24, 26, the two gate valves 13 and 22 are opened. The preliminary washing liquid, previously pumped into the drum 10, can therefore return through the pipes 23 and 16 to the storage tank 18.

In the third operating position of drum 31 the cams 80 are so arranged as to simultaneously operate the switch 71 and changeover valve 61 if, upon closing the switch 90, the side plates 40, 41 are moved towards the drum. Switch 71 causes pump 12 to restart, while pressure fluid drives the gate valve 14 into its open position by means of the pneumatic cylinder 25. Now pure cleaning liquid is delivered from the tank 19 into the drum casing 10.

In the fourth operating position of drum 31, on closing the hand switch 90, the gate valves 14 and 22 are opened by means of the two changeover valves 61, 62 and the pneumatic cylinders 25, 26 so as to permit cleaning liquid to flow from the drum casing 10 back to the storage tank 19.

Should the hand switch 90 be erroneously closed when the drum 31 is not in one of its operating positions, but in an intermediate position, the plates 40, 41 will not be moved towards each other, as then the circuit of the electro-magnet 56 remains open due to the action of the notched disk 33 and the switch 85. The electric connection of the arrangement consequently leads to automatic locking which prevents movement of the plates 40, 41 as long as the drum 31 takes up any intermediate position between consecutive operating positions.

Alternatively, instead of the aforementioned electric arrangement for locking the plates 40, 41 in any intermediate position, a mechanical locking device could be

adopted for the same purpose. This could, for instance, be accomplished by having the locking bolt 82 permanently fixed to the plate 41 and not slidably arranged against the action of spring 83. With the drum 31 in an intermediate position, and with switch 90 closed, the valve 90 opens but the side plates will be prevented from moving towards the drum 31 because the locking bolt 82 strikes against the periphery of drum 31.

If the side plates 40, 41 are moved towards the drum 31, the latter cannot turn because, as already mentioned, the sliding bolt 82 serving as a lock engages in one of the drilled holes 84 of the drum according to FIG. 8.

According to a modified form (not shown), the same result may be attained by means of a lock which comes into and out of engagement with a starwheel arranged on the shaft 38 of drum 31. Thereby the lock need not necessarily be mounted on one of the side plates 40, 41, as it suffices to have it acted on in some known manner in synchronism with the movement of said plates.

For automatic operation of the arrangement the following additional means are provided: According to FIGS. 4 and 6, the shaft 38 of drum 31 carries a ratchet wheel 101 associated with a pawl 102. The latter is arranged on a piston-rod 103 of a piston 104 that is movably guided in a pneumatic cylinder 105 against the action of a spring 106. The cylinder 105 is stationary. A stop 107 is adapted to limit the forward movement of pawl 102. The end of cylinder 105 opposite the spring 106 is joined to a pipe 108 which, according to FIG. 1, is connected through a valve 109 to the distributor pipe 55. The parts 101-107 together constitute a motor-drive in the form of a pneumatically operated ratchet gearing for turning the drum 31. The valve 109 is operated by an electromagnet 110 having in its circuit an electric switch 111 which is also visible in FIGS. 2 and 3. The switch 111 is arranged on the frame 39 of the drum switch and, under spring action, always tends to take up its position of rest in which the connected circuit is closed. An actuating element of the switch 111 cooperates with the extension 44 of plate 40, being operated thereby.

The shaft 38 of drum 31 is hollow and has arranged therein a longitudinally slidable control rod 115. The control rod 115 is under the action of a spring 116 which tends to shift it to the left in FIG. 4, so that its one end protrudes from the center of the handwheel 32. The other extremity of the control rod 115 carries a locking disk 117 with a flange 118 that is provided with two axial grooves 119 and 120 (FIG. 7). Said locking disk has fixed thereto a driving pin 121 that engages in a drilled hole of the ratchet wheel 101, thus coupling the locking disk 117 to the drum 31 (FIG. 4). In the range of the locking disk 117 there is an endwise slidable locking bolt 122 radially arranged thereto, which is under the action of a spring 123 and thus designed as a spring-loaded catch. The width of the two aforementioned grooves 119 and 120 is such that, when the disk 117 and the drum 31 are suitably positioned, the locking bolt 122 can enter one of the grooves. The bottom of one groove 119 is inclined to the axis of disk 117 so that, upon axial displacement of disk 117—in FIG. 4 to the right—said bolt will be pushed back against the action of spring 123. The other groove 120, however, is so shaped that the bolt 122 need not be pushed back in order to pass through. The aforementioned changeover switch 91 for selecting manual or automatic operation is fixed behind the locking disk 117 and provided with an actuating element 125 which bears on the circular back of disk 117 by means of a feeler roller 126. The changeover switch 91 includes a spring which tends to change the switch over to manual operation.

With automatic operation, the functions carried out by switch 90 with manual operation are taken over by two switches 130 and 131 of an impulse transmitter whose design is shown in FIG. 9. The impulse transmitter includes a synchronous motor 132 as a timer which drives two preferably exchangeable cam disks 134 and 135

adapted to operate the two switches 130 and 131. Each of said switches 130 and 131 contains a feeler lever 136 and 137 respectively, as an actuating element, the lever sliding over the periphery of the one or the other cam disk. Switch 130 contains a spring which tends to bring it to a position of rest in which the connected circuit is opened. In the contrast thereto, the other switch 131 includes a spring that always tends to bring the switch to a position of rest in which the connected circuit is closed. The cams along the periphery of disks 134 and 135 are so formed that the lifting flank is sloped, whereas the falling flank is radial to the disk, so that the feeler levers 136 and 137 slide gradually up to the cam face and, in a certain predetermined position of the disk, drop suddenly into their position of rest. The electric circuit is such that one camdisk 134 always determines the beginning and the other camdisk 135 the end of an electric control impulse, in each case the radial falling flank of the cams being determinative, as will be apparent from the description of operation further below. The synchronous motor 132 also drives an indexing disk 140 having a single circumferential notch 141. Said disk 140 has associated therewith an electric switch 142 whose actuating element is a feeler lever 143 sliding thereover. Switch 142 lies in the supply circuit to the synchronous motor 132. A spring built into switch 142 tends to bring it to its position of rest in which the circuit to the synchronous motor 132 is opened.

The action of the parts provided for automatic operation of the arrangement is as follows:

In order to have the arrangement changed over from manual operation to automatic operation, the rod 115 is shifted to the right by pressure applied to its extremity protruding from the center of the handwheel 32, against the action of spring 116 in FIG. 4. Previously, by suitably turning the handwheel 32, the drum 31 and the locking disk 117 coupled thereto were brought into a predetermined initial position in which the groove 119 is opposite the locking bolt 122. On pressing said rod in the said direction, the inclined bottom of groove 119 slides under the bolt 122, thus pressing the latter back against the action of spring 123 until its drops on the opposite side of disk 117. The bolt 122 then locks the disk 117 and rod 115 against movement to the left in FIG. 4. In its new position the disk 117 holds the changeover switch 91 in the position necessary for automatic operation in which the circuit 75 is disconnected from the switch 90 but is connected to the synchronous motor 132 and the two switches 130 and 131 (FIG. 1). Thus the synchronous motor 132 of the impulse transmitter is started. By means (not shown), say, a relay circuit, provision is made that, when changing over to automatic operation, switch 142 is initially briefly short-circuited until the indexing disk 140 has turned through a certain angle and the notch 141 has moved clear of the feeler lever 143 so that the switch 142 is closed. The synchronous motor now continues to run until the notch 141 again reaches the feeler lever 143. When the latter drops into the notch 141, the circuit to the synchronous motor 132 is automatically opened.

As the synchronous motor runs, the cams of the two disks 134, 135 pass under the feeler levers 136 and 137. It is now best to observe the development of the periphery of the feeler disks according to FIG. 10. At first the ends of the feeler levers cooperative with the camdisks are positioned at the extreme left in FIG. 10 on the cams A and A'. Switch 130 is then closed and switch 131 open. Through changeover switch 91, the closed switch 130 and the closed switch 85, the electro-magnet 56 becomes energized and the valve 57 is opened so that compressed air flows into cylinder 48, and the side plates 40, 41 are moved towards the drum 31. Control of the first operation now takes place as disclosed with reference to the manual operation of the arrangement.

After a predetermined period of time the feeler lever

136 falls down the radial flank of the cam A of disk 134, the switch 130 is opened instantly and the circuit to electromagnet 56 is opened. The first electric control impulse A'' is completed; the plates 40, 41 move clear of the drum 31, the switch 111 being operated to close the circuit to the magnet 110. The latter opens the valve 109 which permits compressed air to flow into cylinder 105 so that the piston 104 and pawl 102 in FIG. 6 are moved upwards. Upon engagement of the pawl 102 with the ratchet wheel 101, the latter will be turned sufficiently to cause the drum 31 to take up its next operating position, this taking but a few seconds. Shortly thereafter, the feeler lever 137 falls down the radial flank of the cam A' of disk 135, the switch 131 being closed instantly to initiate a new control impulse B''. Incidentally the circuit to the electro-magnet will be closed anew and, by means of the valve 57 and cylinder 48, the plates 40, 41 are again removed towards the drum 31, thus initiating the second operation as disclosed hereinbefore. Movement of the plates 40, 41 towards the drum 31 again causes the switch 111 to open, thus opening the circuit to the electro-magnet 110. The valve 109 therefore shuts off the air supply to cylinder 105, which is vented by means of valve 109. The pawl 102 returns to its initial position under the action of spring 106.

During this operation the feeler lever 136 gradually runs up the sloping flank of cam B so as to reclose switch 130. Somewhat later the feeler lever 137 also runs up the sloping flank B', whereby switch 131 opens. As the other switch 130 was closed previously, the electro-magnet 56 remains energized until the feeler lever 136 falls down the radial flank of cam B, thus completing the second electric control impulse B''. The plates 40, 41 again move clear of drum 31, thus causing the switch 111 to reclose, thereby again starting the ratchet gearing via electromagnet 110, valve 109 and cylinder 105. The drum will be controlled automatically into the third operating position, whereupon the third operation commences as soon as the feeler lever 137 falls down the radial flank of cam B', thus causing switch 131 to reclose and the third electric control impulse C'' to start. Finally, in an entirely similar way the fourth and last operation takes place under the control of the electric impulse D''. Following this, drum 31 and locking disk 117 reach a position in which the groove 120 comes into the range of the locking bolt 122. Rod 115 and locking bolt 117 are restored to their initial positions under the action of spring 116, whereby the groove 120 passes over the bolt 122. Thus the changeover switch 91 returns to its initial position in which the arrangement will be switched to manual operation.

The description of the method of operation clearly shows that both the start and the end of each electric control impulse A'', B'', C'' and D'' are determined by the radial flanks of the cams of the two disks 134 and 135. In this way hitherto unknown accuracy of the duration and relative timing of the control impulses are obtained. It is also possible to make the intervals between consecutive control impulses very short as compared with the duration of the whole automatic program so that the whole operating cycle can be accelerated.

FIGS. 11 and 12 illustrate further a particularly suitable design of a structural unit with the gate valve 13 and the associated pneumatic cylinder 24. Both the gate valve 13 and cylinder with the piston movable therein are commercial-type elements. Said gate valve includes a pivotal actuating lever 150 and a removable cover 150 whose top has arranged thereon a forked carrier 152. By means of a hinge-pin 153 said carrier swivably supports a retaining ring 154 having the cylinder 24 mounted thereon. The piston-rod 155 projecting from the cylinder 24 is associated with the pivotal lever 150 through a joint 156. The positions of cylinder 24, piston-rod 155 and lever 150 when the piston (not visible) is in its one end position,

with the gate valve 13 closed, are shown in solid lines in FIG. 11. The positions of the said parts with the piston in its other end position and the gate valve 13 opened, are shown in broken lines.

5 The gate valve 14 and cylinder 25, together with gate valve 22 and cylinder 26 are likewise component parts of structural units of the kind described and shown in FIGS. 11 and 12.

10 It is understood that in the described arrangement a pressure liquid may be used instead of compressed air. It is also possible to replace the pneumatic or hydraulic cylinders with their pistons by electro-magnets with movable armatures. Instead of the ratchet gearing 101-107 another motor-driven device may be provided for turning the drum, say, a synchronous motor that is supplied directly by impulses from an impulse transmitter.

15 Where necessary, the drum switch could include only one side plate instead of the two plates 40 and 41 if, in particular cases, comparatively few electric switches and/or valves need to be actuated in the operations to be controlled.

20 What we claim is:

25 1. Apparatus for controlling a sequence of different operations, particularly in a chemical cleaning machine, comprising a drum switch having a control drum with cams thereon, a frame with side plates, a plurality of electric switches on the side plates, a sliding bolt for actuating each electric switch and mounted on the side plates, at least one side plate being pivotally mounted and movable into two positions and the distance of the plate from the axis of said drum being variable to permit the sliding bolts to be lifted off said cams of the drum switch on rotation of the latter, and at least one locking bolt on one of the side plates to engage the drum switch to secure said drum switch from turning as long as the side plate is being moved towards the same.

30 2. Apparatus according to claim 1 in which means are provided to mechanically couple the side plates to each other with the drum being positioned therebetween.

35 3. Apparatus according to claim 1, in which means are provided to mechanically couple the side plates to each other with the drum being positioned therebetween, and in which a fluid operated cylinder and piston is provided connected to the plates, and a motor means for the drum switch drivingly associated therewith.

40 4. Apparatus for controlling a sequence of different operations, particularly of a chemical cleaning machine, comprising a drum switch having a control drum with cams thereon, a frame with side plates, a plurality of electric switches on the side plates, a sliding bolt for actuating each electric switch and mounted on the side plates, the side plates being pivotally mounted and coupled to each other with the drum switch being positioned therebetween, and movable into two positions, the distance of the plates from the axis of said drum switch being variable to permit the sliding bolts to be lifted off said cams of the drum switch on rotation of the latter, at least one locking bolt on one of the side plates to engage the drum switch to secure said drum switch from turning as long as the side plate is being moved towards the same, a fluid operated cylinder and piston connected to the plates, a motor means for the drum switch drivingly associated therewith, a handwheel connected to the drum switch and having a hollow shaft with a rod therein and a spring on the rod, said rod being manually longitudinally displaceable against the action of the spring, a switch for inserting and disconnecting the motor means and having a locking disk with at least one axial groove,

45 5. Apparatus according to claim 4, in which means are provided to mount the locking disk for rotation with said drum switch, and a bolt on the frame to engage the locking disk adapted to hold said rod in its displaced position, said drum switch being rotated by said motor-drive, and said groove of the locking disk passing over said bolt as said drum reaches a predetermined position.

5. Apparatus according to claim 4, in which the locking disk includes a second axial groove having its bottom sloped relative to the axis, the bolt being a spring-loaded catch with means on displacement of the rod, to be pushed back in a second pre-determined position of the drum switch so as to be capable of falling-in on the opposite side of said disk to retain said rod in its position provided for driving the drum switch.
